Primary Examiner — Andrew S Lo(74) *Attorney, Agent, or Firm* — Hanrahan Law Firm, P.A.; Benjamin M. Hanrahan, Esq.(57) **ABSTRACT**

An aerobic step platform assembly is presented herein. The assembly includes a main step platform defining a top surface and a bottom surface, and a plurality of risers each defining a top attachment surface and a bottom surface. The top attachment surface of each riser is removably connected to the bottom surface of the main step platform via an attachment assembly which includes a male portion and a female portion. The male portion includes a peg extending from a surrounding recess, whereas the female portion includes a collar defining a receiving hole. When the attachment assembly is interlocked the peg of the male portion is cooperative with the receiving hole of the collar of the female portion, and the collar of the female portion is cooperative with the surrounding recess of the male portion.

AEROBIC STEP PLATFORM ASSEMBLY

FIELD OF THE INVENTION

The present invention is generally directed to an aerobic step platform assembly, and more specifically, to an aerobic step platform assembly that includes a plurality of risers that are removably connected to a main platform via a cooperatively coupled, interlocking or nesting attachment assembly that provides a secure connection therebetween.

BACKGROUND OF THE INVENTION

Aerobic exercise or aerobic activities can be defined as physical exercise involving virtually any level of intensity (e.g., from low intensity to high intensity) that provides cardiovascular conditioning of various forms. Aerobic exercise can, for example, but need not necessarily include the performance of a repetitive sequence of activities over an extended period of time.

In this manner, step aerobics is a form of an aerobic exercise that can involve the repetitive stepping on and off of a raised platform, or otherwise using a raised platform during an exercise routine that provides cardiovascular conditioning. There are several different routines or exercise programs that can be performed using a raised or step platform, for example, depending on the desired level of intensity or expertise. As an example, one way to increase the intensity level of an exercise routine using a step platform may be to include weights (e.g., held by the exerciser as he/she steps on and off of the platform). Accordingly, in addition to providing an aerobic workout, some routines that utilize a step platform can also provide strength training and other forms of exercise.

Another way to increase the intensity level or expertise level of an exercise routine using a step platform may be to increase the height of the platform, thereby requiring the exerciser to step higher during the routine. In this manner, one or more risers can be placed under the step platform to raise the platform higher, and therefore, to increase the intensity of the workout or exercise routine. However, adding risers beneath the step platform can be dangerous, particularly in the event the risers are not secured or interlocked in some manner to the main platform or to each other. More specifically, the risers should be securely held in place under and to the platform, otherwise the risers can create an unstable and therefore dangerous surface or environment, even during the performance of a low intensity workout.

There is, therefore, a need in the art for an aerobic step platform assembly that provides a secure and stable connection between a main platform (upon which the exerciser will step) and removably attached risers that can be easily added or removed to selectively adjust the height the assembly. It would also be beneficial if, in addition to providing a secure and stable interconnection with the main platform, the risers are easily disconnected or removed, only when desired, in order to allow an exerciser or user to quickly and easily adjust the height of the platform assembly in between exercise routines or even during an exercise routine.

SUMMARY OF THE INVENTION

Accordingly, the present invention is directed to an aerobic step platform assembly with an interlocking or interconnecting attachment assembly that provides a secure and movement restricting connection between a main step platform and at least one, although in many cases a plurality of

2

risers. In particular, the aerobic step platform assembly of at least one embodiment includes an elongated main step platform defining a top surface and a bottom attachment surface. A plurality of risers are also included, each of which define a top attachment surface and a bottom attachment surface. As described in accordance with the various embodiments of the present invention, the risers are removably connectable to the main platform, or to one another, via an interconnecting, interlocking and/or nesting attachment assembly.

More specifically, the attachment assembly is defined as including cooperatively structured portions, at least one portion being formed on or mounted to the main platform, and at least another portion being formed on or mounted to the riser. In some embodiments, the attachment assembly includes a first portion that can also be referred to as a male portion and a second portion that can also be referred to as a female portion that are cooperatively structured such that the first and second portions are removably coupled or interlocked with one another.

In particular, the first or male portion of the attachment assembly of at least one embodiment includes a peg that extends from a surrounding recess formed on the top attachment surface of each of the plurality of risers. The second or female portion of the attachment assembly of at least one embodiment includes a grommet or other like structure that defines an exposed collar formed on the bottom surface of the main platform. The grommet or collar thereof includes a bore or receiving hole disposed at least partially therethrough and which cooperates with the peg of the first or male portion of the attachment assembly.

In this manner, when the first and second portions of the attachment assembly are coupled or interlocked with one another, the peg of the first or male portion is cooperative with or engaged within the receiving hole of the grommet, while the collar of the second or female portion is simultaneously cooperative with or engaged within the surrounding recess of the first or male portion.

Accordingly, when a plurality of first or male portions (e.g., formed on the top attachment surface of the riser(s)) is coupled to a plurality of second or female portions (e.g., formed on the bottom attachment surface of the main platform), lateral, side-to-side, and front-to-back movement between the interconnected or interlocked riser(s) and main platform is restricted via the attachment assembly. Removal of the main platform from the riser(s) or removal of the riser(s) from the main platform can be accomplished by axially pulling the component(s) apart.

Furthermore, in certain embodiments, the bottom surface of each of the risers may also include a plurality of attachment portions that are cooperative with and removably interconnectable to the top attachment surface of another riser. In other words, in the embodiment wherein the top attachment surface of the risers includes a plurality of first or male portions of the attachment assembly, as described above, then the bottom surface of the risers may include a plurality of female portions that are cooperative with the male portions. In this manner, a plurality of similarly constructed risers can be stacked upon one another to selectively adjust the height of the main platform a desired amount while maintaining the movement restricting connection of the attachment assembly.

These and other objects, features and advantages of the present invention will become more apparent when the drawings as well as the detailed description are taken into consideration.

BRIEF DESCRIPTION OF THE DRAWINGS

FIG. 1 is a front perspective view of the aerobic step platform assembly as disclosed in accordance with at least one embodiment of the present invention.

FIG. 2 is an exploded view of the aerobic step platform assembly as disclosed in accordance with at least one embodiment of the present invention.

FIG. 3 is a front elevation view of the aerobic step platform assembly as disclosed in accordance with at least one embodiment of the present invention.

FIG. 4 is another exploded view of the aerobic step platform assembly as disclosed in accordance with at least one embodiment of the present invention.

FIG. 5 is a partial cut-away and exploded view of the aerobic step platform assembly as disclosed in accordance with at least one embodiment of the present invention.

FIG. 6 is a top view of the main platform of the aerobic step platform assembly, as disclosed in accordance with at least one embodiment of the present invention.

FIG. 7 is a bottom view of the main platform of the aerobic step platform assembly as disclosed in accordance with at least one embodiment of the present invention.

FIG. 8 is a bottom view of the aerobic step platform assembly as disclosed in accordance with at least one embodiment of the present invention.

FIG. 9A is a perspective view of the peg of the first or male portion of the attachment assembly as disclosed in accordance with at least one embodiment of the present invention.

FIG. 9B is an elevation view of the peg of the first or male portion of the attachment assembly as disclosed in accordance with at least one embodiment of the present invention.

FIG. 10A a perspective view of the grommet of the second or female portion of the attachment assembly as disclosed in accordance with at least one embodiment of the present invention.

FIG. 10B an elevation view of the grommet of the second or female portion of the attachment assembly as disclosed in accordance with at least one embodiment of the present invention.

Like reference numerals refer to like parts throughout the several views of the drawings provided herein.

DETAILED DESCRIPTION OF THE INVENTION

As shown in the accompanying drawings, and with particular reference to FIGS. 1 and 2, the present invention is directed to an aerobic step platform assembly, generally referenced as 10. In particular, the aerobic step platform assembly 10 of the various embodiments of the present invention includes a main step platform 20 and at least one riser 30a-d. As should be apparent herein, one or more of the risers 30 is/are removably connected, interconnected or otherwise nested with or attached to the main platform 20 in order to selectively raise, lower or otherwise adjust the height of the platform assembly 10 or in order to raise, lower or otherwise adjust the height of a portion or end of the platform assembly 10.

For instance, in at least one embodiment, and as shown in the Figures, one set or level of risers, for example as referenced by 30a, 30b, may be removably connected or attached to the main platform 20 in order to raise the height of the platform assembly 10 by an amount approximately equal to the height of one riser 30a-d. For example, one riser 30a may be connected to one side of the bottom surface of

the main platform 20, while the other riser 30b may be connected to the other side of the bottom surface of the main platform 20.

In this example, and in the embodiment illustrated, the 5 risers 30a-d are all of identical construction. However, it should be noted that in some embodiments, the risers 30a-d may have different heights, lengths, or shapes and still fall within the full spirit and scope of the present invention.

Furthermore, and still referring to FIGS. 1 and 2, for 10 example, the height of the platform assembly 10 can be raised higher by connecting, interconnecting or otherwise attaching another set or a second level of risers, as generally represented as 30c, 30d, to the platform assembly 10. More specifically, the second set of risers 30c, 30d may be 15 removably connected to the bottom surfaces of the first set of risers 30a, 30b in order to raise height of the platform assembly 10 by an additional amount approximately equal to the height of one riser 30a-d or the height of the second set or second layer of risers 30c, 30d.

20 Additional sets or levels of risers (not shown) can be added to the bottom of the aerobic step platform assembly 10 in order to raise the assembly 10 even higher, if desired.

It should also be noted that the risers 30a-d need not be 25 connected to the main platform 20 or assembly 10 in lateral pairs or sets, for example, referencing the first set or level of risers as 30a, 30b and the second set or level of risers as 30c, 30d. In other words, if desired, one side of the main platform 20 may be raised higher than the other side, if, for example, more risers 30a-d are connected or interconnected to the 30 main platform 20 or assembly 10 on one side. More specifically, the assembly 10 may be selectively arranged such that any number of risers 30a-d (zero or more) may be connected or interconnected to either one or both of the sides 22a, 22b of the main platform 20.

35 In another embodiment or example, a single riser may span the entire or substantially the entire length of the platform assembly 10 such a level of risers may be defined by a single elongated riser, rather than a set of two risers (e.g., 30a, 30b and 30c, 30d).

40 In any event, the main step platform 20 of at least one embodiment of the present invention comprises a top surface 22, a bottom surface 24, and a plurality of peripheral walls 26a-d. As should be apparent, the top surface 22 is the surface upon which a user will step during performance of 45 one or more exercises using the step platform assembly 10 of the present invention, whereas the bottom surface 24 is opposite to the top surface 22 and generally faces in a downward direction during operative use of the platform assembly 10.

50 Additionally, each of the risers 30a-d of at least one embodiment include or otherwise define a top surface or a top attachment surface, referenced as 32a-d, and an opposing bottom surface or bottom attachment surface, referenced as 34a-d. As described and illustrated herein, the top attachment surfaces 32a-d of the risers 30a-d are selectively and 55 removably attachable to the bottom surface 24 of the main platform 20 via an attachment assembly. More in particular, the attachment assembly of at least one embodiment of the present invention includes a plurality of first portions, for 60 example male portions, represented as 40, and a plurality of cooperatively structured second portions, for example female portions, represented as 50. As described herein, the first, or male portions, and the second, or female portions, of the attachment assembly cooperate with one another in order to selectively connect or interconnect the riser(s) 30a-d to the main platform 20 and/or to one another in a stacked manner.

For instance, in at least one embodiment, and as illustrated in FIG. 2, the first or male portions 40 of the attachment assembly may be formed on or extend from the top attachment surfaces 32a-d of the risers 30a-d. In this manner, the cooperative second or female portions 50 of the attachment assembly may be formed on the bottom surface 24 of the main platform 20. It should also be noted that other embodiments may include a reverse configuration, for example, with the first or male portions 40 of the attachment assembly being formed on or extending from the bottom surface 24 of the main platform 20, and with the second or female portions 50 of the attachment assembly being formed on the top attachment surfaces 32a-d of the risers 30a-d.

Furthermore, still referring to FIG. 2, the first or male portions 40 of the attachment assembly of at least one embodiment of the present invention include at least one peg, rod or pin, referenced as 42, which cooperatively engages with or connects to a corresponding second or female portion 50, as described herein. As shown, the peg 42 of the first or male portion 40 of the attachment assembly extends beyond an immediately surrounding or adjacent portion of the top attachment surface 32a-d to which the peg 42 is secured. This allows the peg 42 to extend into a corresponding second or female portion 50 of the attachment assembly, as described herein, although it should be noted that other configurations are contemplated.

Furthermore, and still referring to FIG. 2, the peg 42 of at least one embodiment of the present invention extends from a surrounding recess 44. More specifically, the recess 44 as used herein is defined as a depression, cavity or socket formed into the top attachment surface 32a-d of the riser 30a-d. In this manner, the first or male portion 40 of the attachment assembly of at least one embodiment of the present invention includes a recess 44 that dips into the top attachment surface 32a-d, and a peg 42 extending from the recess 44 and including a distal end 43 that is disposed beyond or above the immediately surrounding portion of the top attachment surface 32a-d. Put another way, the distal end 43 of the peg 42 may extend beyond a top circumferential edge 45 of the surrounding recess 44. In some cases, the top circumferential edge 45 of the recess 44 may meet at the immediately surrounding portion of the top attachment surface 32a-d. Accordingly, and in other words, in at least one embodiment, the peg 42 of the first or male portion 40 of the attachment assembly includes a length that is greater than a depth of the surrounding recess, thereby allowing the peg 42 to extend from the bottom surface of the recess and beyond the top circumferential edge 45 thereof.

Furthermore, the peg 42 of the exemplary embodiment is coaxial with the surrounding recess 44 in that the peg 42 extends from the center of the recess 44. However, in other embodiments (not illustrated), the peg 42 may not be coaxial with the surrounding recess 44 and may still fall within the full spirit and scope of the present invention.

Moreover, as shown in the exemplary embodiment of FIG. 2, the recess 44 includes a circular shape or configuration, however, other embodiments may include a recess of virtually any shape and still fall within the full spirit and scope of the present invention. For example, as described herein, the recess 44 of the first or male portion 40 of the attachment assembly is shaped and configured to receive or at least partially receive a collar 54 of the second or female portion 50. In this manner, the recess 44 and the collar 54 of at least one embodiment are cooperatively constructed or cooperatively sized and shaped such that the collar 54 is able to fit within or at least partially within the recess 44, for example, in a snug or movement restricting manner.

More specifically, the second or female portion 50 of the attachment assembly of at least one embodiment includes a collar 54 which may protrude or extend at least partially from the surrounding surface, such as the immediately surrounding bottom surface 24 of the main platform 20 or the immediately surrounding bottom surface 34 of a riser 30a-d. In particular, as previously mentioned, the collar 54 of the second or female portion 50 of the attachment assembly is cooperatively shaped and sized with the recess 44 of the first or male portion 40 of the attachment assembly such that when the first or male portion 40 is removably connected to the second or female portion, the collar 54 is at least partially engaged or disposed within the recess 44.

In addition, as shown in FIGS. 5 and 7, for example, the second or female portion 50 of the attachment assembly also defines a receiving hole, bore or channel 55 with at least one open end 55a. The receiving hole or channel 55 is cooperatively formed or constructed with the peg 42 of the first or male portion 40 such that the peg 42 is removably engaged or disposed within the hole 55 when the first or male portion 40 is removably connected to the second or female portion 50. In other words, the distal end 43 of the peg 42 will pass through the open end 55a of the receiving hole 55 allowing the peg 42 to engage within the hole 55.

In this manner, a removable connection between the first or male portion 40 and the second or female portion 50 of the attachment assembly is accomplished when the peg 42 of the first or male portion 40 is cooperative with or otherwise disposed or engaged within the receiving hole 55 of the second or female portion 50, and when the collar 54 of the second or female portion 50 is cooperative with or otherwise disposed or engaged within the recess 44 of the first or male portion 40. Such a cooperative engagement between with first or male portion 40 and the second or female portion 50 of the attachment assembly restricts lateral movement (e.g., side-to-side or front-to-back movement) between two engaged pieces (e.g., between the main platform 20 and a riser 30a-d, and/or between one riser and another connected or stacked riser). The attachment assembly may be disengaged through axial movement of one piece relative to the other, for example, by axially pulling or separating the main platform 20 from a connected riser 30a-d, by axially pulling or separating a riser 30a-d from a connected main platform 20, or by axially pulling or separating one riser from another stacked or connected riser.

Additionally, as mentioned herein, and as shown in the exemplary embodiment of FIGS. 2 and 4-8, the main platform 20 includes a plurality of second or female portions 50 of the attachment assembly disposed on the bottom surface 24 thereof, for removable connection with a plurality of first or male portions 40 that are disposed on the top attachment surface 32a-d of a corresponding riser 30a-d. Furthermore, as shown in FIGS. 4 and 8, in at least one embodiment, each of the risers 30a-d include a plurality of female portions 50 and/or collars 54 disposed on the bottom surfaces 34a-d thereof. The female portions 50 and/or collars 54 disposed on the bottom surfaces 34a-d of the risers 30a-d are cooperative with or otherwise removably engageable with the male portions 40. This allows the risers 30a-d to be selectively connectable to one another or otherwise stacked upon one another in order to change or adjust the height of the platform assembly 10. Of course, as mentioned above, a reverse configuration may be contemplated such that the top attachment surfaces 32a-d of the risers 30a-d are equipped with or include female portions and wherein the bottom surfaces 34a-d are equipped within or include male portions, as used herein.

It is also worth noting that, in at least one embodiment, each of the risers **30a-d** are interchangeable and include identical constructions or configurations. In some embodiments, however, the risers **30a-d** may be formed of or include differing heights to provide additional customization or height selection.

With reference to FIG. 7, a bottom view of the main platform **20** of at least one embodiment is shown. Particularly, in at least one embodiment, the main platform **20** includes a first set of attachment portions, generally referenced as **62a-d** and a second set of attachment portions, generally referenced as **64a-d**. As shown, the first set of attachment portions **62a-d** are disposed on one side or on one half of the main platform **20**, while the second set of attachment portions **64a-d** are disposed on the other side or other half of the main platform **20**. In this manner, the risers **30a-d** each include a set of attachment portions (e.g., a plurality of first or male portions **40**) which separately cooperate with the first set **62a-d** and the second set **64a-d** of attachment portions on the bottom of the main platform. More specifically, using the set of attachment portions on the top surface of the riser **30a-d**, the riser **30a-d** can be attached to the first set **62a-d** or the second set **64a-d** of the attachment portions on the bottom of the main platform **20**.

In this manner, the first and second set of attachment portions **62a-d**, **64a-d** may be female portions **50** (as shown in the FIGS.) or, in an alternative embodiment, male portions **40**. Of course, if the first and second set of attachment portions **62a-d**, **64a-d** are female portions **50**, then the set of attachment portions on the top surface **32a-d** of the risers **30a-d** will be cooperative male portions **40**, as shown in the Figures. Alternatively, if the first and second set of attachment portions **62a-d**, **64a-d** are male portions **40**, then the set of attachment portions on the top surface **32a-d** of the risers **30a-d** will be cooperative female portions **50**.

Furthermore, the attachment assembly of at least one embodiment may also include a third portion defined as another set of attachment portions formed on or included on the bottom surfaces **34a-d** of the risers **30a-d**. The third portions or set of attachment portions formed on the bottom surface **34a-d** of the riser **30a-d** is cooperative with the set of attachment portions that are formed on the top attachment surfaces **32a-d** of the risers **30a-d**. More specifically, if the set of attachment portions on the top attachment surfaces **32a-d** of the risers are male portions **40**, then the set of attachment portions on the bottom surfaces **34a-d** of the risers **30a-d** will be cooperative female portions **50**, as shown in the Figures. Alternatively, if the set of attachment portions on the top attachment surfaces **32a-d** of the risers **30a-d** are female portions **50**, then the set of attachment portions on the bottom surfaces **34a-d** of the risers **30a-d** will be cooperative male portions **50**.

With reference now to FIGS. 9A-10B an exemplary peg **42** (FIGS. 9A and 9B) of the first or male portion **40** of the attachment assembly, and an exemplary grommet **52** defining the collar of the second or female portion **50** of the attachment assembly is shown.

Particularly, with reference first to FIG. 9A, the peg **42** of at least one embodiment may be defined as including an exposed shaft **42a** extending from a mounting base **42b** and terminating at distal end **43**. The mounting base **42b** of at least one embodiment may include enlarged collars **42c** separated by a recessed column **42d**, although other structures and configurations of the mounting base **42b** and/or peg **42** are contemplated within the full spirit and scope of the various embodiments of the present invention described herein. Particularly, the mounting base **42b** operates to

fixedly mount the peg **42** to the corresponding riser **30a-d**. In this manner, the mounting base **42b**, or a substantial portion of the mounting base **42b**, may be embedded within or fixed to the body of the riser **30a-d** with the exposed shaft **42a** extending therefrom and terminating at the distal end **43**.

Referring now to FIG. 10A, the grommet **52** of at least one embodiment includes or otherwise defines the collar **54** and receiving hole **55** discussed herein with reference to the second or female portion **50** of the attachment assembly. In at least one embodiment, the grommet **52** also includes a mounting collar **54b** and column **54c**, as shown. Particularly, the mounting collar **54b** and column **54c** of at least one embodiment is structured such that the grommet **52** is fixed to or mounted to the corresponding main platform **20** and/or riser **30a-d**. In this manner, the mounting collar **54b** and the mounting column **54c** may be embedded, at least partially embedded within or mounted to the body of the main platform **20** or riser **30a-d** with the collar **54** extending therefrom in the manner described herein.

With reference to FIGS. 9B and 10B, elevation views of the peg **42** and grommet **52** of at least one embodiment are shown for purposes of illustrating some dimensions thereof. For example, the exposed shaft **42a** of the peg **42** may include a length referenced as *L* and measured between the first collar **42c** and the distal end **43**. Similarly, the receiving hole **55** of the grommet **52** may include a depth *D* measured from the open end **55a** to a bottom closed end **55b** thereof. In an exemplary embodiment, the length *L* of the peg **42** or exposed shaft **42a** thereof may be equal to, substantially equal to or be slightly less than the depth *D* of the receiving hole **55**. As just an example, in at least one embodiment, the length *L* may be approximately fifteen millimeters (15 mm) while the depth *D* may be approximately sixteen millimeters (16 mm), although other lengths *L* and depths *D* greater or smaller are contemplated and still within the spirit and scope of the present invention.

Furthermore, and still referring to FIGS. 9B and 10B, the peg **42** and/or the exposed shaft **42a** thereof may include a width that is sized to engage within or be disposed within the receiving hole **55** of the grommet **52**. In this manner, the width *W1* of the peg **42** may be equal to, substantially equal to, slightly more or slightly less than the width *W2* of the receiving hole **55**. More specifically, the peg **42** may be constructed of a rigid material, including but in no way limited to metal or a rigid plastic material, whereas the grommet **52** may be constructed of a resilient or pliable material such as, for example, rubber or other like material. Accordingly, the width *W2* of the receiving hole **55** may be substantially equal to or slightly smaller than the width *W1* of the peg **42**, which allows the peg **42** to be securely connected to or engaged within the hole **55** to prevent or minimize inadvertent axial disconnection there between. As just an example, the width *W1* of the peg **42** may be approximately ten millimeters (10 mm), whereas the width *W2* of the hole **55** may be approximately 9.7 millimeters (9.7 mm), although other widths *W1*, *W2* are contemplated.

Additional features of at least one embodiment of the present invention include one or more nesting components which cooperatively allow the riser(s) **30a-d** to nest, mate or telescopically connect with the bottom surface of the main platform **20** and/or with another stacked riser. In particular, with reference again to FIGS. 2 and 5, the risers **30a-d** of at least one embodiment include at least one raised wall referenced as **70** extending from the top attachment surface **32a-d**. In some embodiments, the raised wall **70** is a continuous wall disposed around the perimeter of an interior

opening or defining an interior opening although other configurations are contemplated. In this manner, as shown in FIG. 5, for example, the bottom surface 24 of the main platform 20 includes a corresponding recess defined by walls 80 within which the raised walls 70 of the risers 30a-d are nested. For example, the outer surfaces 72 of raised walls 70 will face or nest with the inner surfaces of walls 80. This nesting feature further restricts lateral movement of the riser(s) 30a-d during operation of any exercises upon the platform assembly 10.

Furthermore, in some embodiments, one or more additional walls or steps 75 may also extend from the top attachment surfaces 32a-d of the risers 30a-d, for example against or adjacent outside surfaces 72 of walls 70. In the embodiment shown, the additional walls or steps 75 are shorter in height when compared to the wall(s) 70, although other configurations are contemplated.

Furthermore, still referring to FIG. 5, the main platform 20 of at least one embodiment of the present invention includes corresponding recesses or indents 85 that mate or nest with the additional walls or steps 75. The mating or nesting walls 75 and recesses 85 provide additional restrictions upon lateral movements of the connected platform 20 and riser 30a-d, for example, during use.

Similarly, it should be noted that the risers 30a-d of at least one embodiment, and in particular, the underside thereof, include corresponding walls and recesses that cooperatively mate or nest with the raised walls or steps 70, 75 of another riser 30a-d. In particular, the underside of the risers 30a-d of at least one embodiment of the present invention, include an inner recess to receive raised wall(s) 70 of a stacking riser, and edge recesses 95 to receive the additional step or walls 75. In this manner, stacked risers can be nested with one another in order to restrict lateral movement there between during operation of the platform assembly 10 of the present invention.

With reference again to FIGS. 1-6, yet another feature of at least one embodiment of the present invention includes one or more recessed channels, referenced as 27a-d, disposed on or along one or more of the peripheral edges or walls 26a-d of the main platform 20. More specifically, the recessed channels 27a-d can be used by an individual or exerciser as a hand grip or finger hold during the performance of an exercise using the platform assembly 10 of the present invention. For instance, with the user's palm on the top surface 22 or on the edge between the top surface 22 and the peripheral wall 27a-d, the user can grip the platform 20 by engaging or placing his or her fingers within the one or more recessed channels 27a-d. Such a position can be helpful for the user to maintain his or her position or balance during use of the platform assembly 10 in various manners. As just an example, the user or exerciser may grip onto the platform 10 in the manner described above using the recessed channel(s) 27a-d in order to perform push-ups, lunges, stretches, or other various exercises.

Accordingly, in at least one embodiment, the main platform 20 may include elongated recessed 27a-d along each of the peripheral edges or walls 26a-d, although in some embodiments, one or more of the peripherals edges or walls 26a-d may not include a recessed channel.

In the embodiment shown, for example, recessed channel 27a is disposed on corresponding peripheral wall 26a and extends substantially the entire length of the longitudinal peripheral wall 26a, allowing the user or exerciser to form a grip in the manner disclosed above in substantially any position along the length of the wall 26a. It should be noted, however, that in other embodiments, the recessed channel

26a may be substantially smaller, may extend along only a portion of the wall 26a, or may be sectioned such that the wall 26a may include a plurality of recessed channels spaced there along.

5 Similarly, recessed channel 27b is disposed on corresponding lateral or end peripheral wall 26b and extends substantially the entire length of the lateral or end peripheral wall 26b, allowing the user or exerciser to form a grip in the manner disclosed above in substantially any position along the length of the wall 26b. It should be noted, however, that in other embodiments, the recessed channel 26b may be substantially smaller, may extend along only a portion of the wall 26b, or may be sectioned such that the wall 26b may include a plurality of recessed channels spaced there along.

10 Further, recessed channel 27c is disposed on corresponding longitudinal peripheral wall 26c and extends substantially the entire length of the peripheral wall 26c, allowing the user or exerciser to form a grip in the manner disclosed above in substantially any position along the length of the wall 26c. It should be noted, however, that in other embodiments, the recessed channel 26c may be substantially smaller, may extend along only a portion of the wall 26c, or may be sectioned such that the wall 26c may include a plurality of recessed channels spaced there along.

15 Finally, recessed channel 27d is disposed on corresponding lateral or end peripheral wall 26d and extends substantially the entire length of the lateral or end peripheral wall 26d, allowing the user or exerciser to form a grip in the manner disclosed above in substantially any position along the length of the wall 26d. It should be noted, however, that in other embodiments, the recessed channel 26d may be substantially smaller, may extend along only a portion of the wall 26d, or may be sectioned such that the wall 26d may include a plurality of recessed channels spaced there along.

20 Since other modifications and changes varied to fit particular operating requirements and environments will be apparent to those skilled in the art, the invention is not considered limited to the example chosen for purposes of disclosure, and covers all changes and modifications which do not constitute departures from the true spirit and scope of this invention. This written description provides an illustrative explanation and/or account of the present invention. It may be possible to deliver equivalent benefits using variations of the specific embodiments, without departing from the inventive concept. This description and these drawings, therefore, are to be regarded as illustrative and not restrictive.

25 Now that the invention has been described,
What is claimed is:

30 1. An aerobic step platform assembly, comprising:
a main step platform comprising a top surface and a bottom surface,
a plurality of risers each comprising a top attachment surface and a bottom surface,
35 said main step platform comprising a plurality of collars extending from said bottom surface of said main step platform, each of said plurality of collars comprising a receiving hole disposed therein,
40 each of said plurality of risers comprising a plurality of pegs and a plurality of surrounding recesses, wherein each of said plurality of pegs comprises a mounting base and a shaft, said mounting base being fixedly mounted to a corresponding one of said plurality of risers with said shaft extending from a corresponding one of said plurality of surrounding recesses, wherein said mounting base comprises at least two enlarged collars separated by a recessed column,

11

wherein each of said plurality of pegs is removably disposable at least partially within a corresponding one of said plurality of receiving holes of said plurality of collars extending from said bottom surface of said main step platform, and

wherein said plurality of collars are cooperatively sized with said plurality of surrounding recesses such that when said plurality of pegs of one of said plurality of risers are disposed within said receiving holes of corresponding ones of said plurality of collars, said corresponding ones of said plurality of collars are removably disposed in a movement restricting manner within said surrounding recesses of said corresponding ones of said plurality of collars.

2. An aerobic step platform assembly, comprising: a main step platform comprising a top surface and a bottom surface,

a plurality of risers each comprising a top attachment surface and a bottom surface,

a plurality of attachment assemblies, each comprising: a first portion and a second portion,

said first portion and said second portion being cooperatively removably coupled to one another,

said first portion comprising a peg and a surrounding recess, said peg comprising a mounting base and a shaft, said peg being fixedly mounted within said surrounding recess via said mounting base with said shaft being coaxial with and extending from said surrounding recess, wherein said mounting base comprises at least two enlarged collars separated by a recessed column,

said second portion comprising a collar protruding from a surrounding surface and defining a receiving hole disposed therein,

wherein said peg of said first portion is removably disposable at least partially within said receiving hole of said collar of said second portion,

wherein said collar of said second portion and said surrounding recess of said first portion are cooperatively sized such that when said peg is disposed at least partially within said receiving hole of said collar, said collar is removably disposed within said surrounding recess of said first portion,

12

wherein said bottom surface of said main step platform comprises a first set of attachment portions disposed on one half of said main step platform and a second set of attachment portions disposed on another half of said main step platform, said first set of attachment portions and said second set of attachment portions each comprise a plurality of said second portions of said attachment assemblies, wherein said surrounding surface is on said bottom surface of said main platform,

wherein each of said plurality of risers comprise a set of first portions of said attachment assemblies disposed on said top attachment surface,

wherein said set of first portions disposed on said top attachment surface of said risers is selectively attachable with said first set of attachment portions on said bottom surface of said main step platform, and

wherein said set of first portions disposed on said top surface of said risers is also separately attachable with said second set of attachment portions on said bottom surface of said main step platform.

3. The aerobic step platform assembly as recited in claim

2 wherein said attachment assemblies further comprise a third portion, wherein said bottom surface of each of said plurality of risers comprises a set of a plurality of said third portions removably connectable to a set of first portions disposed on a top surface of another one of said plurality of risers.

4. The aerobic step platform assembly as recited in claim 3 wherein said at least one peg of said first portion of each of said attachment assemblies comprises a distal end that extends beyond a top edge of said surrounding recess.

5. The aerobic step platform assembly as recited in claim 4 wherein said surrounding recess comprises a depth and said at least one peg comprises a length, said length of said peg being greater than said depth of said surrounding recess.

6. The aerobic step platform assembly as recited in claim 2 wherein said main step platform comprises a plurality of peripheral walls, wherein at least one of said plurality of peripheral walls comprises an elongated recessed channel disposed thereon, said elongated recessed channel being configured to provide a finger hold for a user during performance of an exercise.
